United States Patent Office

Des. 205,563
Patented August 16, 1966

205,563

AIRPLANE

Arthur E. Flock, Jr., Atlanta, Ga., assignor to Lockheed
Aircraft Corporation, Burbank, Calif.

Filed July 28, 1965, Ser. No. 86,332

Term of patent 14 years

(Cl. D71—1)

FIG. 1

FIG. 2

FIG. 3

FIG. 4

FIGURE 1 is a perspective view taken from the top front of an airplane embodying the present design;

FIGURE 2 is a front elevation thereof;

FIGURE 3 is a side elevation thereof; and

FIGURE 4 is a top plan view thereof.

I claim:

The ornamental design for an airplane, substantially as shown.
